United States Patent Office.

FREDERICK M. MAAS, OF NEW YORK, N. Y.

Design No. 3,581, dated July 13, 1869.

DESIGN FOR A TRADE-MARK.

The Schedule referred to in these Letters Patent and making part of the same.

To all whom it may concern:

Be it known that I, FREDERICK M. MAAS, of New York, in the county and State of New York, have originated and designed a new Design for Marking Manufactured Goods, such as leather and similar articles, as a trade-mark; of which the following is a full, clear, and exact description, reference being had to the accompanying drawings, making part of this specification.

This invention is intended as a trade-mark, more particularly for leather or hides; and consists in the design of an old-fashioned ship, A, having three masts *n m r*, with sails set, sailing towards the left, and with a lone star, *x*, over the main-mast *n*.

The ship is represented surrounded by water.

Below this design the letters "N. R. & Co." are placed.

The above-described design may be cut either in wood or metal, and stamped upon the article, or the same be engraved and embossed upon the desired article; or in some cases, the same may be cut out of a thin sheet of metal, making a stencil, and then, by means of a suitable brush, painted, through means of this stencil upon the article.

What I claim as my invention, and desire to secure by Letters Patent, is—

The herein-described design or configuration, as a trade-mark.

FREDERICK M. MAAS.
